UNITED STATES PATENT OFFICE

ALEXANDER FORSYTH, OF AURORA, ILLINOIS.

MACHINE FOR GRINDING LOCOMOTIVE-FRAMES.

No. 888,604.

Specification of Letters Patent.

Patented May 26, 1908.

Application filed April 20, 1906. Serial No. 312,831.

To all whom it may concern:

Be it known that I, ALEXANDER FORSYTH, a citizen of the United States, residing at Aurora, in the county of Kane and State of Illinois, have invented certain new and useful Improvements in Machines for Grinding Locomotive-Frames, of which the following is a specification.

My invention relates to grinding machines, and has for its object to provide a machine of this type adapted for use in grinding the jaws of locomotive frames in place of filing them.

My invention consists in the details and combinations hereinafter described and claimed.

In the accompanying drawings—Figure 1 is a front elevation of a portion of a locomotive frame, showing my grinding machine in position for operation. Fig. 2 is a sectional end elevation on the line 2 of Fig. 1. Fig. 3 is a similar view on the line 3 of Fig. 1. Fig. 4 is a top plan view of the grinding device. Fig. 5 is a sectional view of the grinding device, taken on the line 5 of Fig. 1. Fig. 6 is a bottom plan view of my improved grinding device, partly in section. Fig. 7 is a sectional view on the line 7 of Fig. 4. Fig. 8 is a top plan view of the clamp. Fig. 9 is a top plan view of a part of the supporting frame, partly in section.

In the drawings, *a* represents a locomotive frame, having, as is usual, the jaws *a'*, *a''*, the inner face of the jaw *a'* being vertical and the inner face of the jaw *a''* being inclined as shown in Fig. 1.

b represents, generally, my improved grinding machine, comprising a supporting frame, having vertical members *b'* connected at the top by the clamping member *b''* and at the bottom by a suitable connecting block *b''*, the members *b'* being rabbeted on their inner sides to form dovetailed guides or ways, for a purpose hereinafter described. Formed integrally with these vertical members is a cross bar *b³*, extending laterally from each side of the vertical members, and provided with recesses *b⁴*, *b⁵* to allow the passage of the moving parts of the grinding device.

50 The laterally extending portions of this horizontal bar are secured to portions of the locomotive frame by suitable clamps *b⁶*, as indicated in Fig. 1.

The clamp for securing the supporting frame at the top is formed of a horizontal

member *b³* and a downturned vertical member *b⁵*, the member *b³* being secured by suitable bolts *b⁴* to the vertical members of the supporting frame.

b⁶ indicates a screw passing through the downturned end *b⁵* and bearing against the locomotive frame for securing the supporting frame in position.

c indicates, generally, my improved grinding machine, comprising a sliding block *c'*, 65 sliding in the dovetail ways formed in the inner faces of the vertical members of the supporting frame.

c² represents, generally, my improved grinding or cutting device, and *c³* an air 70 motor connected by a train of gears *c⁵* with the grinding device.

c⁴ represents a supply pipe for furnishing compressed air to the motor.

Referring now more especially to Figs. 4 75 and 5, these figures show the details of my improved grinding device. As before stated, this grinding device is secured to the sliding block *c'*, and consists of a frame *c⁶*, having outwardly extending arms *c⁷*, *c⁸*, formed at 80 their outer ends with bearing recesses, which recesses form one-half of the bearing for a shaft *d*—the other portions of the bearing *c¹⁰* being suitably secured by bolts, or other fastening devices, to the outwardly extending portions *c⁷*, *c⁸*. At one side, on the left,—as shown in Fig. 5—the shaft *d* is supported directly in its bearing. On the other side, a gear wheel *c⁹*, forming a part of the train of gears *c⁵*, is mounted upon the shaft, 90 the shaft and gear wheel being keyed together by a key *d²*—the shaft being provided with a key-way *d³*, permitting the shaft to slide longitudinally with respect to the gear wheel, but turned therewith.

The gear wheel *c⁹* is mounted in the bearing in the arm *c⁸*, the collar of the gear wheel being formed with a circumferential groove *c¹⁵* receiving the bearing and preventing longitudinal movement of the gear wheel. 100 On the ends of this shaft are mounted the grinder *e*. The shaft is formed midway of its length with spaced collars *d⁴*, and a nut *d⁵* is mounted therebetween. Adjusting screws *d⁶*, provided with plain end portions or end bearing portions *d⁷*, are mounted in the outwardly extending bearing arms *c⁷*, *c⁸*, the screw threaded portion of these screws passing through screw threaded perforations in the nut *d⁵*. These screws are operated by a 110

worm shaft d^{10} , having worms d^9 formed thereon, engaging worm wheels d^8 on the ends of the screws. A hand-wheel d^{11} is provided on the shaft d^{10} for operating it. It will now be readily understood that when the hand-wheel d^{11} is turned, the shaft d is moved to one side or the other to bring the grinder e into engagement with one of the faces of the locomotive frame jaws. As shown in Fig. 1, the grinder wheel e is in engagement with the vertical jaw of the frame.

f represents an elongated screw mounted between the vertical members of the supporting frame, as indicated in Figs. 1, 3, 4, 5 and 7. It has a bearing f' at the top of this frame, and is provided with a head f^2 . This elongated screw passes through a screw threaded lug or block g secured to the rear of the sliding block b' upon which the grinding device and its motor are mounted. Thus it will be seen that when the screw is rotated, the grinding device and the motor are caused to travel up or down, depending upon the direction of rotation of the screw. At its lower end the screw passes through a worm wheel h , having an elongated collar h' , as clearly shown in Fig. 7. The screw is keyed to this worm wheel so as to turn therewith, at the same time having a longitudinal movement therewith, as will be readily understood. The worm wheel h is rotated by a worm h^3 mounted upon a shaft h^5 secured in suitable bearings beneath the motor.

h^4 represents a gear on the worm shaft h^5 , which gear engages a gear wheel c^{13} forming a part of the train of gears c^5 . Thus it will be seen that when the motor is in operation, not only does it operate the grinding device, but it also operates the raising and lowering device for feeding the mechanism vertically.

The train of gears c^5 consists of the gear wheels c^9 , c^{10} , c^{11} , c^{12} , c^{13} and c^{14} . The gear wheels c^{13} and c^{14} are mounted upon oppositely extending arms k' , k^2 of a swinging frame k which is mounted for swinging movement upon the shaft h^5 . This frame is provided with a handle k^3 upon which is mounted a pivoted locking lever k^5 , having an angular extension k^6 at one end, which engages with one of a series of recesses l' in the segment l secured to the motor frame. By operating this lever, the frame k may be swung so as to bring either one of the gears c^{13} or c^{14} into engagement with the gear c^{12} . Thus is provided a means for changing the direction of rotation of the grinding wheels and of the feeding device, as will be readily understood.

As shown in Fig. 1, the parts are in position to operate upon the vertical jaw of the locomotive frame. When it is desired to operate upon the inclined jaw, the grinding wheels are shifted through the hand-wheel d^{11} ,—as before described—and in order to bring the surface of the grinding wheel into parallel relation with the surface to be oper-

ated upon, I provide the following devices. The clamp b^3 is provided with an adjusting screw m passing through the horizontal member of the clamp and engaging the top of the locomotive frame at one side of its longitudinal center. When it is desired to bring the grinding wheels into parallel relation with the inclined jaw, the clamps b^7 , b^8 are loosened and the screw m turned so as to raise that side of the clamp b^3 in which the screw is mounted. This will cause the supporting frame and the mechanism carried thereby to tilt slightly. When in proper position, the clamp b^3 is tightened and the clamps b^7 again applied, so as to secure the lateral extensions of the horizontal bar b^2 to the portions of the locomotive frame.

It is believed that the operation of my improved grinding machine will be understood without further description.

On reference to the drawings, it will be seen that the locomotive frame is substantially U-shaped and that the machine which embodies my invention is designed and adapted to grind the inner faces of the legs of the U. It will also be observed that the frame of the machine consists of two members crossing each other at right angles, thus making a cross-shaped frame. One end of one arm of the cross is adapted to be attached to the base of the U-shaped frame and both ends of the other arm of the cross are adapted to be attached to the frame at its respective sides.

I claim:

1. A machine for facing locomotive frame jaws having in combination a supporting frame, means for attaching the supporting frame to the locomotive frame jaws, a carriage adjustably mounted on said supporting frame, a rotary grinder comprising a shaft and grinding wheels and a motor for operating said grinder mounted on said carriage, means connected to the motor and actuated thereby for automatically moving the carriage on the frame, and means for moving the grinder shaft longitudinally thereof relatively to the carriage.

2. In a machine for facing locomotive jaws, a supporting frame, a carriage adjustably mounted on the frame, a rotary grinder comprising a longitudinally adjustable shaft having grinding wheels mounted on the carriage, a motor also mounted on the carriage and connected to the grinder for operating the grinder, and means whereby the carriage is automatically adjusted when the motor is in operation.

3. In a machine for facing locomotive frame jaws comprising a supporting frame having a grinder and a motor adjustably mounted thereon, said grinder comprising a shaft having grinding wheels at each end thereof, means for connecting the supporting frame to the locomotive frame, and means for

adjusting the position of the supporting frame with reference to the locomotive frame jaws.

4. A machine for grinding the inner faces of the legs of a **U**-shaped frame, comprising a supporting frame having the general shape of a cross, one end of one arm of the cross being adapted to engage the base of the **U**-shaped frame and the ends of the other arm being adapted to engage the **U**-shaped frame at the sides thereof, a motor mounted on the cross-shaped frame, and a grinding member driven by said motor.

5. A machine for grinding the inner faces of the legs of a **U**-shaped frame, comprising a supporting frame having the general shape of a cross, one end of one arm of the cross being adapted to engage the base of the **U**-shaped frame and the ends of the other arm being adapted to engage the **U**-shaped frame at the side thereof, a carriage mounted

on the cross frame and adapted to reciprocate parallel to the legs of the **U**-frame, a transverse shaft on the carriage having grinding wheels at each end thereof, a motor 25 on the carriage, and gearing connecting the said shaft and motor.

6. A machine for grinding the inner faces of a **U**-shaped frame with slightly diverging legs, comprising a supporting frame adapted 30 to be pivotally secured at one end to the base of the **U**-frame, a cross shaft with grinding wheels at the ends thereof, and means whereby the said supporting frame may be swung on its pivot so as to bring the said cross-shaft at right angles to the inner face of either 35 leg of the **U**-frame.

ALEXANDER FORSYTH.
